UNITED STATES PATENT OFFICE.

JOSIAH TAYLOR, OF LOCK NO. 4, MONONGAHELA RIVER, PENNSYLVANIA.

IMPROVEMENT IN SASH FOR HOT-BEDS, &c.

Specification forming part of Letters Patent No. 136,789, dated March 11, 1873.

To all whom it may concern:

Be it known that I, JOSIAH TAYLOR, of Lock No. 4, Monongahela River, Washington county, in the State of Pennsylvania, have invented a certain new and useful Improvement in Sash for Hot-Beds, &c.; and I do hereby declare that the following is a full, clear, and exact description thereof, reference being had to the accompanying drawing and to the letters of reference marked thereon.

My invention relates to an improved mode of constructing sash for hot-beds, &c., in sections, and securing two or more of said sections together in the manner hereinafter described.

To enable others skilled in the art to make and use my invention, I will proceed to describe more fully its construction and operation.

In the accompanying drawing which forms part of my specification, Figure 1 is a top view or plan of my improvement in sash for hot-beds, &c. Fig. 2 is a transverse section of the same.

In the accompanying drawing, A and B represent the side rails, C the center rails, and D end pieces of the sash. The rails A, B, and C are provided with grooves f, in which are placed strips of gum e, so that the edges of the panes of glass will press against the sides of the gum strips by forcing the side rails toward the center rail C, through the medium of the rods g and screw-nuts h. The form of the rails A, B, and C, and the arrangement of the gum strips e in them, are clearly indicated in Fig. 2. The lower edge of the rail B, about midway between its ends, is provided with a

hook l, constructed of heavy hoop-iron, and the rail A is provided with a cap-piece, K, for the purpose of covering the joint formed when uniting together the several sections of the sash, as indicated in Fig. 2 at x.

In connection with the hook l for holding together two or more sashes, screws may be used, as indicated at m.

By constructing a sash, as hereinbefore described, the glass when broken can be readily removed and new glass substituted, and the side edges n of the panes of glass i will be perfectly packed, which will prevent the leakage of water through the joints; and by the peculiar form of the side rails B, which are provided with the hooks l, two or more sashes can be united and manipulated together, which is a great consideration when used for hot-beds in gardens. The sash hereinbefore described can also be used with great advantage as "sky-lights" in buildings.

The advantage of protecting the joints by the caps K and packing the edges of the glass in the manner described will be apparent to builders.

Having thus described my improvement, what I claim as of my invention, is—

In a sash for hot-beds or skylights, the combination and arrangement of the rails A, B, C, ends D, caps K, rods g, hook l, gum strips e, and glass i, all constructed and arranged with relation to each other as hereinbefore described, and for the purpose set forth.

JOSIAH TAYLOR.
